UNITED STATES PATENT OFFICE

167,898

ROOM AIR CONDITIONING UNIT

Bernard W. Jewell, Wichita, Kans., assignor to
The O. A. Sutton Corporation, Inc., Wichita,
Kans., a corporation of Kansas

Application January 2, 1952, Serial No. 17,895

Term of patent 14 years

(Cl. D62—4)

To all whom it may concern:

Be it known that I, Bernard W. Jewell, a citizen of the United States of America, residing at Wichita, county of Sedgwick, State of Kansas, have invented a new, original, and ornamental Design for a Room Air Conditioning Unit, of which the following is a specification, reference being had to the accompanying drawing, forming part hereof.

Fig. 1 is a front view in elevation of the room air conditioning unit showing my new design, the air directing nozzles being adjusted to direct air horizontally forward;

Fig. 2 is a side view in elevation of the room air conditioning unit showing my new design, the nozzles being directed upwardly;

Fig. 3 is a side view in elevation of the opposite side of the room air conditioning unit;

Fig. 4 is a front view in elevation, on a reduced scale, showing the nozzles directed forwardly in opposite directions;

Fig. 5 is a plan view of Fig. 4;

Fig. 6 is a bottom view of Fig. 4;

Fig. 7 is a horizontal section of a detail, on an

enlarged scale, taken along the line marked 7 in Fig. 4;

Fig. 8 is a vertical section, on an enlarged scale, taken along line 8—8 of Fig. 4; and

Fig. 9 is a horizontal section, on an enlarged scale, taken along the line marked 9 in Fig. 4.

The essential features of my design reside in the portions shown in full lines.

I claim:

The ornamental design for a room air conditioning unit, as shown and described.

BERNARD W. JEWELL.
